UNITED STATES PATENT OFFICE.

EDWIN FAY HOPKINS, OF WOODSTOCK, ILLINOIS, ASSIGNOR OF ONE-HALF
TO GARDNER ELIJAH BURBANK, OF SAME PLACE.

DESIGN FOR A MEDAL.

SPECIFICATION forming part of Design No. 22,037, dated December 6, 1892.

Application filed September 22, 1892. Serial No. 446,625. Term of patent 3½ years.

To all whom it may concern:

Be it known that I, EDWIN FAY HOPKINS, residing at Woodstock, in the county of McHenry and State of Illinois, have invented a certain new and useful Design for Medals, of which the following, when taken in connection with the drawings accompanying and forming a part hereof, is a full and complete description sufficient to enable those skilled in the art to understand, make, and use the same.

In the drawings, Figure 1 is a front view of the reverse side of the medal; Fig. 2, a front view of the obverse side; and Fig. 3, a sectional view on line 33 of Fig. 1, viewed in the direction indicated by the arrows.

My invention consists of a circular medal

having on the obverse side thereof a ship or schooner and on the reverse side the figure of a hog, the ship and the hog being in bas-relief with a circular bas-relief border on both the obverse and reverse sides of the medal. In the drawings the ship is lettered A, the hog B, and the borders C and D, respectively.

Having thus described my invention, what I claim as new, and desire to be Letters Patent, is—

The design for a medal, as herein shown and described.

EDWIN FAY HOPKINS.
